UNITED STATES PATENT OFFICE.

WALTER C. BECKWITH, OF FOSTORIA, OHIO, ASSIGNOR TO THE BEVINGTON SIGNAL COMPANY, OF SAME PLACE.

DESIGN FOR A LANTERN-BODY.

SPECIFICATION forming part of Design No. 18,716, dated November 6, 1888.

Application filed August 1, 1888. Serial No. 281,695. Term of patent 3½ years.

To all whom it may concern:

Be it known that I, WALTER C. BECKWITH, a citizen of the United States, and a resident of the town of Fostoria, in the county of Seneca and State of Ohio, have invented a certain new and useful Design for a Lantern-Body, of which the following is a specification.

The design is particularly applicable to lanterns for campaign purposes, it being somewhat characteristic of one of the present political parties.

In the accompanying drawing the figure shows a lantern embodying my design.

The lantern is ornamented by a series of colored bands, (marked *r*, *w*, and *b*.) and which extend vertically on the surface of the glass globe. Between the bands are clear interspaces *a*, of greater or less width. These clear interspaces may be omitted, the colored bands

then coming in contact with each other. The colors employed give a handsome and beautiful effect.

The lanterns having the ornamentation as herein described are very attractive and form objects of beauty, valuable aside from their use for campaigning purposes.

What I claim as new, and desire to secure by Letters Patent, is—

The design for lanterns herein described and shown, consisting of a lantern-body the outline of which is substantially an ogee curve, and a series of vertically - arranged stripes thereon, substantially as set forth.

W. C. BECKWITH.
